US0D1073493S

(12) **United States Design Patent** (10) **Patent No.:** **US D1,073,493 S**
(45) **Date of Patent:** **** May 6, 2025**

(54) **AIR QUALITY DETECTOR**

(71) Applicant: **Jinpeng Yi**, Shenzhen (CN)

(72) Inventor: **Jinpeng Yi**, Shenzhen (CN)

(**) Term: **15 Years**

(21) Appl. No.: **29/923,946**

(22) Filed: **Jan. 3, 2024**

(51) **LOC (15) Cl.** **10-04**

(52) **U.S. Cl.**

USPC **D10/53; D10/57**

(57) **CLAIM**

The ornamental design for an air quality detector, as shown and described.

DESCRIPTION

FIG. 1 is a front, top and right side perspective view of an air quality detector, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 shown in FIG. 4 thereof.

The broken lines shown in the drawings illustrate portions of the air quality detector that form no part of the claimed design.

The dot-dash broken lines shown in FIGS. 4 and 9 represent the designation of an enlargement view and form no part thereof.

1 Claim, 9 Drawing Sheets
